GRATE

Donald J. Mosshart, Ardmore, Pa., assignor to
Westinghouse Electric Corporation, East Pittsburgh, Pa., a corporation of Pennsylvania

Application July 24, 1944, Serial No. 546,295

3 Claims. (Cl. 110—38)

This invention relates to stokers, more particularly to those of the "spreader" or "sprinkler" type, and has for an object to provide improved grate structure therefor.

Yet another object of the invention is to provide improved composite grate bars of inverted-V formation, together with novel means for reciprocating at least a portion of such bars to provide for movement of the fuel bed thereover.

These and other objects are effected by the invention as will be apparent from the following description and claims taken in connection with the accompanying drawings, forming a part of this application, in which:

Fig. 1 is a longitudinal sectional view taken along the line I—I of Fig. 2, looking in the direction indicated by the arrows;

Fig. 2 is a transverse sectional view taken along the line II—II of Fig. 1, looking in the direction indicated by the arrows;

Fig. 3 is an enlarged fragmentary exploded view of one of the stationary grate bars;

Fig. 4 is an exploded sectional view taken along the line IV—IV of Fig. 3, looking in the direction indicated by the arrows; and

Fig. 5 is an enlarged fragmentary sectional view taken along the line V—V of Fig. 2, looking in the direction indicated by the arrows.

Referring now to the drawings more in detail, the reference character 10 indicates, in its entirety, stoker mechanism of the sprinkler or spreader type and including grate structure 11 disposed within a furnace 12 which has the usual side walls 13, rear wall 14 and front wall 15. The latter is provided with an opening 16 through which fuel is impelled by the blades 17 of the rotary impeller 18, to the fuel supporting surface of the grate structure 11. The mechanism for feeding fuel into the furnace through the front wall opening 16 forms no part of the present invention and, therefore, is not further described herein. However, if desired, it may take the form disclosed in applicant's copending application, Serial No. 549,848, filed August 17, 1944.

The grate structure 11 comprises a plurality of reciprocating grate bars 20 alternating with stationary grate bars 21 and disposed in side-by-side relation. While in the arrangement herein illustrated, alternate bars are reciprocating and the remaining bars stationary, it will be apparent that this particular arrangement of reciprocating and stationary bars may be varied if desired.

As best shown in Fig. 2, the bars are composite and of inverted V form and extend transversely

of the furnace with the central apex substantially aligned with the longitudinal center of the furnace, directly to the rear of the fuel feed opening 16 in the furnace front wall 15. All of 5 the bars rest at their outer ends on supporting plates 22, having disposed therebeneath and therebeyond conventional dump plates 23, carried by oscillatable shafts 24.

Each composite reciprocatory bar 20 includes 10 a central upper member 26 having lateral downwardly-inclined side portions 27, an end bar member 28 and one or more intermediate bar members 29, together with a supporting rod or strip 30 disposed beneath the bar members 26, 15 28 and 29 and secured thereto by suitable means, such as the pins 31 extending therethrough and through depending lugs 32 aligned therewith. Each of the bar members 26, 28 and 29 is of inverted U cross section and comprises an upper 20 fuel-supporting portion 34, depending side members 35 and 36 and laterally extending ribs 37 and 38 (Figs. 1 and 5). The supporting rod 30 is disposed between the depending side pieces 35 and 36 and is secured thereto by the pins 31, 25 as previously indicated.

Preferably, each of the end bar members 28 and intermediate bars members 29 are provided at their upper ends with projections 39 and 40, respectively, adapted to be received in mating 30 recesses 41 and 42 provided in the adjacent ends of the bar members next thereabove.

Each central upper member 26 is provided with 35 a depending transversely-extending web or rib 44 having a notch 45 formed in its lower surface for reception of the upper flange 46 of a structural I member 47 which extends longitudinally of the grate structure 11 and is supported for limited transverse reciprocatory movement upon, and fixed to, a plurality of carriage structures 40 48, supported on rollers 49 mounted upon shafts 50 carried by frame structures 51, which in turn are supported by a pair of longitudinally-extending structural members 52.

The frames 51 carry bearings 53 for a shaft 54 45 extending from front to rear of the furnace and having keyed thereto a plurality of crankarms 55, connected through links 56 with the carriages 48, whereby limited oscillatory movement of the shaft 54 produces corresponding lateral reciprocating movement of the I-beam 47. Inasmuch 50 as the upper flange 46 of this beam is received in the groove 45 in the depending lugs 44 of the reciprocating bars 20, the latter will have reciprocating motion imparted thereto. Limited oscillatory movement is imparted to the shaft 54 by 55

the stoker drive engine 60, through gearing 61 and linkage 62 and 63.

The space below the grate structure 11 is provided with a pair of longitudinally-extending walls 65 and 66 of masonry or other suitable material, with structural members 67 and 68 disposed thereon, and, the combined structure forming vertical supports for the supporting plates 22, on which the outer ends of the grate bars rest. A pair of longitudinally-extending partitions 70 and 71 divide the space below the grate structure 11 and between the vertical walls 65 and 66 into a central plenum chamber 72 and side plenum chambers 73 and 74. The upper edges of the partitions 70 and 71 abut the lower flanges of structural members 75 and 76, respectively, which serve as intermediate supports for the stationary bars 21.

Suitable means (not shown) may be provided for controlling the relative supplies of air to the three plenum chambers 72, 73 and 74. Inasmuch as, under certain operating conditions, the quantities of air supplied to the various plenum chambers may differ, it is desirable to prevent, insofar as possible, leakage of air from one chamber to another. To this end the grate bars 20 and 21 are provided with depending sealing structures adapted to cooperate with the plates 77, mounted on the upper edges of the structural members 75 and 76, to prevent leakage of air over the upper edges of the partition structure 70 and 71. As best shown in Fig. 5, each reciprocating grate bar 20 carries a sealing structure comprising a depending block 80, having upwardly-extending spaced ears 81 straddling the supporting rod 30 and secured to the latter by pins 82, the ears 81 fitting between the depending side pieces 35 and 36 of the grate bar member. The lower portion of the depending block 80 is provided with a transversely-extending slot 83, in which is positioned a sealing member 84 in the form of a transversely-extending strip, which, as the bar reciprocates, is adapted to slide back and forth across the plates 77 forming the top wall of the partitions 70 and 71.

The stationary bars 21 are very similar in structure to the reciprocating bars 20 except that they omit the depending web or rib 44, as shown in Fig. 3, and are provided with intermediate depending support members 86 and 87 adapted to rest upon the upper surfaces of the structural members 52, 75 and 76.

The sealing structure for the stationary bars differs from that of the reciprocating bars in that, inasmuch as they do not move, "floating" sealing member 84 is omitted. Instead, the depending web 86 directly engages the plates 77, carried by the top of the structural member 75. The sealing structure for each stationary bar is supported therefrom in the same manner as the sealing structures for the reciprocating bars.

In operation, fuel is thrown by the blades 17 of the rotary impeller 18 rearwardly through the furnace front wall opening 16 onto the upper surface of the grate structure 11, along a central

path extending from front to rear of the grate structure in overlying relation to the central plenum chamber 72. The transverse movement of the reciprocating alternate bars 20 with respect to the stationary bars 21, feeds the fuel laterally in both directions from the central zone overlying the central plenum chamber, across the end bars 28 overlying the side plenum chambers 73 and 74, to the dump plates 23.

While the invention has been shown in but one form, it will be obvious to those skilled in the art that it is not so limited, but is susceptible of various changes and modifications without departing from the spirit thereof, and it is desired, therefore, that only such limitations shall be placed thereupon as are specifically set forth in the appended claims.

What is claimed is:

1. In a furnace, grate structure comprising a plurality of transversely-extending grate bars of inverted-V shape disposed in side-by-side relation, a number of said bars being transversely reciprocable and being interspersed among the remaining stationary bars; wall structure cooperating with the grate structure to provide beneath the latter a plenum space; a pair of partitions disposed longitudinally of the plenum space and extending from the bottom of said space to points adjacent the under surface of the grate structure, said partitions separating the plenum space into a central plenum chamber and a pair of side plenum chambers; and a sealing member carried by and depending from each of the grate bars and sealing the space between said bars and the tops of the partitions therebeneath, whereby flow of air from one plenum chamber to another is prevented.

2. In a furnace, a grate structure comprising a plurality of transversely-extending grate bars of inverted-V shape disposed in side-by-side relation, a number of said bars being transversely reciprocable and being interspersed among the remaining stationary bars; a pair of structural members extending longitudinally of the furnace grate structure beneath the latter to support the stationary bars from beneath at points intermediate their apexes and ends; a pair of longitudinal partitions extending downwardly from the pair of structural supporting members and separating the space beneath the grate structure into a central plenum chamber and a pair of side plenum chambers, and separate sealing members carried by each of the bars for preventing flow of air from one plenum chamber to another between the top of the structural supporting members and the bottom of said bars.

3. Structure as specified in claim 2, wherein the structural supporting members have horizontal upper surfaces against which the sealing members abut, and the sealing members carried by the reciprocable bars automatically maintain sealing engagement with said horizontal surfaces during reciprocation of the bars.

DONALD J. MOSSHART.
